FATTY ACID AMIDO-METHIONINE PRODUCTS

This application is a continuation in part of copending application Ser. No. 672,975, filed Oct. 5, 1967 now abandoned.

This invention relates to compounds resulting from the acylation of methionine with fatty acids. The compounds of this invention possess interesting properties for use in the therapeutic and cosmetic fields, and more especially, the the treatment of human phaners, i.e., finger nails and hair, because of their chemical structure and their combination of water-insolubility and lino-solubility.

The compounds of the present invention are fatty acid amido-methionines having the following formula:

wherein R is an aliphatic hydrocarbon chain of five to 29 carbon atoms, thereby making RCO the acyl grouping from a fatty acid of six to 30 carbon atoms.

It has been known in the past that aminoacids could be acylated but that acylation has always resulted in surface active agents or detergents, generally in the form of highly detergent water-soluble, sodium salts, which were unsuitable for the purpose of the present invention.

In accordance with the present invention, there are provided compounds consisting of fatty acid amido-methionines of the formula:

wherein R is an aliphatic hydrocarbon chain of five to 29 carbon atoms.

The compounds of this invention are prepared by acylating methionine with a fatty acid or a fatty acid halide to produce a fatty acid amido-methionine salt. The obtained salt is treated with a strong acid or a cationic ion exchange resin to obtain the corresponding fatty acid amido-methionine.

The products of the present invention are particularly suitable for use in fields of therapeutics and cosmetics since they are lipo-soluble and their structure is similar to the structures of human phaners. These properties provide the products with the capability of penetrating easily through the tissues of finger nails, toe nails, hair, etc., and they are accordingly useful in promoting regeneration of such tissues by providing the most important aminoacid which is needed for this purpose, i.e., methionine.

Methionine is one of the most important of the aminoacids for at least two reasons. Firstly, it contains sulfur which is essential in the protidic structures of the phaners; secondly, it is more important than cystine and cysteine—which also contain sulfur—for, in the case of a deficiency in one of these aminoacids, methionine is able to convert into cystine and/or cysteine to reduce the deficiency. Proof of this conversion has been established by an experimentation using tagged sulfur in methionine.

Methionine in the form of fatty acid amido-methionines is especially interesting for this kind of structure. It is biosynthesized in an organism by the action of acylcoenzyme A whereas the corresponding methionine is freed from this structure by the action of SH-coenzyme A.

The products of the present invention are preferably prepared in a two-step process as described above.

The acylation is carried out by treatment of the methionine with a fatty acid or its functional equivalent, i.e. a fatty acid halide. The acids or the acid halides, the preferred halide being chloride, are those which contain six to 30 carbon atoms 5 and may be saturated or unsaturated. Among these acids may be mentioned caproic, enanthic, caprylic, pelargonic, capric, undecanoic, lauric, tridecanoic, myristic, pentadecanoic, palmitic, margaric, stearic, nonadecanoic, eicosanoic, heneicosanoic, behenic, tricosanoic, lignoceric, pentacosanoic, 10 cerotic, heptacosanoic, octacosanoic, nonacosanoic, triacontanoic, undecenoic, myristoleic, palmitoleic, oleic, erucic, and the like. It is intended, of course, that the naming of the foregoing acids includes the naming of their halides, such as 15 chlorides, bromides, iodides, and fluorides, chlorides being the preferred halide. In general, the reaction takes place at ordinary temperatures, for example, 20°-60° C. and the pH is maintained on the alkaline side, i.e. at about 7.5 to 11 by the addition of a suitable material such as sodium hydroxide, sodium carbonate, ethyl chlorocarbonate, and the like. The reaction time varies with temperature but may require from about 20 15 minutes to several hours.

The acylation reaction may be considered to proceed generally as follows:

35 If the acylating agent is a free acid the byproduct of the equation is water and, if on the other hand, the acylating agent is an acid chloride, the byproduct is hydrogen chloride. In order to displace this reaction to the right, the byproduct water or hydrogen chloride should be removed as quickly as it is formed, which explains the reason for employing an alkaline material when hydrogen chloride is the byproduct. If sodium hydroxide is employed as the alkaline agent it also tends to react with the acylating agent thus making it preferable to employ a slight stoichiometric excess of the acylating agent to provide enough for the principal reaction, for the reaction 40 with the alkaline agent, and to force displacement of the reaction to the right.

45

The final step consists in treating the acylation product with a strong mineral acid such as hydrogen chloride or with an ion exchange resin. In one embodiment of this invention, the 50 acylation product is acidified with hydrogen chloride and the compound of the invention accumulates as an upper layer, since it is insoluble in water, while the remaining material which is soluble remains in the aqueous layer.

55 In order to more fully understand the present invention, there is provided a detailed example in which a fatty acid amido-methionine is prepared. In general, the time, temperature, and other reaction conditions have been selected to give the best possible yield for each reaction. It is understood that 60 modifications of these conditions can be made by those skilled in the art without deviating from the spirit of this invention. Parts and percentages are by weight and temperatures are in degrees centigrade unless otherwise specified.

EXAMPLE 1

First Step: Acylation

a. By Acid Chloride

Methionine is dissolved in water at the rate of about half a mole per liter and there is added sodium hydroxide and sodium carbonate to reach a pH of about 10-11. Separately palmitic acid chloride mixed with acetone is prepared and then poured under agitation at room temperature in the methionine solution until stoichiometric proportions between methionine and palmitic chloride are obtained; pH values are controlled.

by the addition of sodium carbonate to prevent the pH from being lower than 8. After the end of the addition the agitation is continued for 4 hours. The solution is ready for the second step.

b. By the Free Acid

To an aqueous solution containing one part of methionine there is added concentration sodium hydroxide until a concentration of 2N is obtained and the solution is then chilled to a temperature between -5° and -10° C. A solution containing the stoichiometric amount of palmitic acid dissolved in ten times its volume of tetrahydrofuran is prepared, to which is added, by reference to the volume of the acid, 0.5 parts of ethyl chlorocarbonate and 0.7 parts of triethylamine. This solution of palmitic acid is then likewise cooled to a temperature between -5° and -10° C. and slowly poured into the solution containing the methionine. The two solutions are mixed by agitation and the resulting mixture is cooled to prevent any rise in temperature during this step.

Other mixtures are possible for obtaining the compounds of the invention by using the free acid as starting material. It is possible to obtain the result while performing the reaction in the presence, for instance, of dicyclohexylcarbodiimide.

Second step: Recovery of Product

The compound of the invention is recovered in the same manner whether the acylation agent is the acid chloride or the free acid. In either event the acylation product is acidified with an acid such as hydrogen chloride and the fatty acid amido-methionine which is insoluble in water accumulates as a layer on top of the aqueous layer. After decanting the supernatant layer, it is washed with water several times and then with benzene or other solvent to remove the last portions of palmitic acid or its chloride which may be present. The washed material is then steamed in a vacuum at a temperature of 50° C. and the fatty acid amido-methionine, i.e., palmitoyl methionine is obtained. The product has a melting point of 82°-84° C. Acylation yield 90 percent. Analytical values for nitrogen 3.6 percent (Theory 3.2 percent) and sulfur 8 percent (Theory 7.1 percent).

In general, these compounds may be dehydrated by a short heating at 100° C.

EXAMPLES 2-5

The procedure of example 1 was repeated except that different fatty acids or fatty acid chlorides were employed. The acylating agents were caprylic acid and caproyl chloride, lauric acid and lauric acid chloride, undecenoic acid and undecenoyl chloride, linoleic acid and linoleic acid chloride. The main characteristics of the compounds obtained are listed below in table I.

TABLE I

Example	Compounds	Melting point, °C.	Acylation yield, percent	Percent			
				Nitrogen		Sulfur	
	Acyling agent	Found	Theory	Found	Theory		
2.....	Caprylic acid or its chloride.....	73-75	98	4.9	5	11	11.5
3.....	Lauric acid or its chloride.....	68-70	92	3.9	4.2	9.5	9.6
4.....	Undecenoic acid or its chloride.....	57-59	88	4.4	3.9	10	8.4
5.....	Linoleic acid or its chloride.....		93	3.2	3	7.5	7

The present invention relates also to some compositions concerning the treatment of hair and nails and which comprise as an active ingredient therein, at least one of the fatty acid amido-methionines hereinabove described.

Some examples of such compositions are given below.

EXAMPLES 6-7

5	Hair lotions		
	6. Alcohol at 50% (vol.)	98%	

10	Caprylic methionine	2%	
		100%	

7. Alcohol at 70% (vol.)	98%		
Undecenoic methionine	2%		

100%

EXAMPLES 8-9

15	Detergent compositions for hair		
	8. Sodium lauroylsarcosinate at 20%	30%	
	Caprylic methionine	2%	
	Water	68%	
		100%	
20	9. Lauric methionine	10%	
	Water	90%	
	Triethanolamine, (enough to make pH 7)		100%

EXAMPLES 10-11

25	Compositions for nails		
	10. Alcohol at 80% (vol.)	98%	
	Linoleic methionine	2%	
		100%	
30	11. Stearin	10%	
	Polyoxyethylenate cetyllic alcohol	5%	
	Palmitic methionine	4%	
	Water	81%	
		100%	

35 What is claimed is:

1. A water insoluble, lipo-soluble fatty acid amido methionine of the formula

40 wherein R is an aliphatic hydrocarbon chain of 5 to 29 carbon atoms.

2. The compound of claim 1 wherein R is selected from the group consisting of capryl, lauryl, undecenyl, and linoleyl.

3. The process of preparing a fatty acid amido methionine of claim 1 which comprises (a) reacting methionine with a fatty acid or its halide containing 6 to 30 carbon atoms per molecule to produce a fatty acid amido methionine salt, and

45 (b) reacting said salt with a strong acid or a cationic ion exchange resin to produce the desired fatty acid amido

70 methionine.

4. The process of claim 4 wherein said fatty acid or its halide is selected from the group consisting of caprylic acid, caproyl chloride, lauric acid, lauroyl chloride, undecenoic acid, undecenoyl chloride, linoleic acid, and linoleic acid chloride.
